CURRENT CONTROLLING MEANS

Filed July 17, 1924

Inventor
Lawrence C. F. Horle
By Alfred H. Dyson Attorney

UNITED STATES PATENT OFFICE.

LAWRENCE C. F. HORLE, OF NEWARK, NEW JERSEY, ASSIGNEE, BY MESNE ASSIGNMENTS, TO FEDERAL TELEPHONE MANUFACTURING CORPORATION, OF BUFFALO, NEW YORK, A CORPORATION OF NEW YORK.

CURRENT-CONTROLLING MEANS.

Application filed July 17, 1924. Serial No. 726,642.

To all whom it may concern:

Be it known that I, LAWRENCE C. F. HORLE, a citizen of the United States of America, and a resident of Newark, county 5 of Essex, and State of New Jersey, have invented certain new and useful Improvements in Current-Controlling Means, of which the following is a specification.

This invention relates to an improved 10 form of current controlling means adaptable readily to various circuits differing widely as to the voltage drop across them and as to the value of current traversing them. More particularly, the invention relates to a current controlling means which 15 obviates the necessity for the provision of a variety of rheostats to meet differing voltage and current requirements over a wide range.

20 An example of the problem involved in attempting to provide current control means where the current consuming devices to be controlled vary widely as to voltage drop and value of current, and where also current supply sources of a variety of voltages 25 may be used, is met with in the operation of vacuum tubes. Heretofore current controlling means for use with vacuum tubes have been constructed with a narrow range 30 of control, and suitable only for tubes fairly uniform as to filament voltage and current. But with the rapid increase in the number of tube types differing greatly in filament voltage and current, the narrow range controlling means has become inadequate, 35 requiring, as it does, that a number of rheostats varying as to resistance and current carrying capacity must be provided, each best suited in any given installation, to type 40 and number of tubes and to type of battery or other current source supplying the heating current for the filaments. It should be noted that the combinations of filament voltage and current now encountered, and 45 to which the current controlling means must be adapted, are numerous, and also that tubes vary considerably as to the ratio of voltage to current. For example, a list of tubes in common use shows the following

50 figures for filament voltage and current: 5 volts, 1 ampere; 5 volts, .25 ampere; 1.1 volt, .25 ampere; 3 volts, .060 ampere. To add further to the difficulty of adapting the controlling rheostat to the widely varying

tube filament requirements, the introduction 55 of low filament voltage and low filament current tubes has meant a considerable variation in the range of voltage of the source of filament current, usually batteries, which may be used. 60

The general object of this invention is to provide a rheostat construction such that the resistance range and current carrying capacity of the rheostat are capable of meeting a wide variety of voltage and current control requirements. Thus in the particular case of the heating current for the filament of the vacuum tube, it is the object 65 of the invention to avoid the inconvenience and expense heretofore caused by the necessity for providing a number of rheostats to suit different tubes. 70

The object is accomplished for the particular case of the vacuum tube cited, and for similar cases where a number of current 75 consuming devices of different voltage and current characteristics have been heretofore controlled by rheostats of different size, by the provision of a resistance element consisting of a plurality of resistance members 80 connected in series.

The following drawings and description 85 fully and clearly explain the principle and application of the invention.

Fig. 1 is a diagram showing a resistance element in a circuit in which is included a current consuming element and a source of current.

Figure 2 is a plan view of one form of the 90 invention.

Figure 3 is a side elevation of Figure 2. 95

Figure 4 is a cross section on line A A of Figure 2.

Figure 5 is a plan view of another form of the invention.

In the figures the same part will be designated by the same reference character wherever such part is shown in several views:

In the diagram of Figure 1, a resistance element 1 is shown as made up of two sections in series, one, for example, a heavy wire section 2 and the other a fine wire section 3. The element 1 is shown as part of a current controlling device 4, and as connected in circuit with a current consuming element 5 which in the present case is the filament of a vacuum tube, and in circuit 100 105

with a source of current 6 which in the present case is a battery. In the embodiment of the invention shown in Figures 2, 3, and 4, the resistance element 1 is shown as mounted 5 on an insulating and supporting member 7, which is set into the recess 8 of the insulating base 9. A rotatable metal sleeve 10 passes through base 9 and is held in position by plate 11 and by spring washer 12. Contact plate 14 is staked securely to sleeve 10 and rotates with it. Contact finger 15 bears on the resistance wires mounted on member 7. A shaft 16 passes through sleeve 10 and is fastened thereto by set screws 17. Two 10 terminal plates 18 and 19 are fastened to base 9 by screws 20 and 21 respectively. The free end of the heavy wire section 2 of resistance element 1 is connected to terminal plate 18, the connection being made by looping 15 the end of the wire of section 2 under the head of screw 20. Sleeve 10 is connected electrically to terminal plate 19 through plate 11, and screw 21, said screw 21 serving to fasten both plate 11 and terminal plate 19 20 to base 9.

In operation, leads of a circuit, such as illustrated in Figure 1 and containing a current source and a current consuming device, are connected to terminal plates 18 and 30 19. The current path through the rheostat is then as follows: terminal 18, screw 20, part of resistance element 1, contact finger 15, sleeve 10, plate 11, screw 21, terminal plate 19. The desired regulation of 35 current in the circuit is secured by rotating shaft 16 by any suitable means. Movement of the shaft is transmitted through sleeve 10 to contact finger 15 which moves over resistance element 1, thereby varying the 40 amount of resistance in the circuit.

The sections 2 and 3, one of heavy wire and one of fine wire may occupy approximately equal space on the supporting member 7, although this is not essential. In order 45 to carry into effect the objects of the invention, the two sections 2 and 3 are formed respectively of wire of such material and cross section that the current carrying capacity of section 2 is materially higher than 50 that of section 3, and the resistance of section 2 is materially lower than that of section 3. As an example, a rheostat constructed in accordance with my invention may have the following resistance element characteristics: Current carrying capacity of section 2 and section 3 respectively may be 1.8 55 amperes and .75 ampere; resistance of section 2 and section 3 respectively may be 2.2 ohms and 13.8 ohms, or a total resistance for element 1 of 16 ohms.

I do not wish to be understood, however, as limiting myself to the two section arrangement of the resistance element herein described, since more than two sections may be used in making up the resistance element.

Thus, it is practical and desirable to extend the subdivision of the resistance element 1 to a three-section arrangement, and in the embodiment of the invention illustrated in Figure 5, resistance element 22 corresponding to resistance element 1 of Figures 2, 3, 4, is divided into the heavy-wire section 23, next the medium-wire section 24, and finally the fine-wire section 25. As in the case of the two section construction, the three sections of element 22 are connected in series. The other details of construction and operation are the same essentially as described for the two section arrangement. A rheostat constructed in accordance with my invention and carrying the subdivision of the resistance element to three sections, as shown in Figure 5, may have the following resistance element characteristics: Current carrying capacity of sections 23, 24 and 25 respectively may be 2 amperes, 1 ampere and .25 ampere; resistance of sections 23, 24 and 25 respectively may be 1.5 ohms, 4 ohms and 54.5 ohms, or a total resistance of element 22 of 60 ohms. Considering the three sections as they compare with each other in current carrying capacity, and in resistance: The current carrying capacity of heavy-wire section 23 is materially higher than that of medium-wire section 24 (about twice in the case illustrated in Figure 5); the current carrying capacity of medium wire section 24 is, in turn, materially higher than that of fine-wire section 25 (about four times in the case illustrated); but the resistance of heavy-wire section 23 is materially lower than that of medium-wire section 24 (about .4 in the case illustrated); the resistance of medium wire section 24 is, further, very materially lower than that of fine-wire section 25 (about .07 in the case illustrated).

It will be seen that in both the two-section and the three-section arrangement of the resistance element, the current carrying capacity of this element is stepped up, so that the section having low carrying capacity is at the free end of the resistance element and the section having high carrying capacity is at the terminal end of the resistance element (terminal 18 in the figures). On the other hand, the resistance per section is stepped up toward the free end of the resistance element, so that the section of low resistance is at the terminal end of the element (terminal 18) and the section of high resistance is at the free end.

Used with a current consuming device, for example the filament of a vacuum tube, or a plurality of such filaments, having a large voltage drop and requiring a comparatively large current, a rheostat constructed in accordance with my invention will utilize only the heavy-wire section, or a portion thereof, and no other section. But if used with some current consuming device, for example, the

filament of a small vacuum tube, having a small voltage drop and requiring only a small amount of current, the rheostat will utilize all of the sections including such portion of the fine-wire section as is needed to bring the current to the desired value.

It is evident that these extreme cases and a large variety of other cases between these extremes are within the range of a current controlling means constructed in accordance with my invention, merely by adjusting for the proper amount of resistance. In the embodiment of the invention shown in the figures this adjustment is easily accomplished by the rotating of the contact finger over the resistance element.

What is claimed is:

1. In a rheostat, a base member carrying a resistance element comprising in series a comparatively heavy wire coil and a comparatively fine wire coil, a rotatable sleeve journaled in said base and adapted to be fastened to an actuating shaft and carrying a contact finger in slidable engagement with said resistance element, and means associated with said base and independent of said

shaft for holding said sleeve and attached finger in alignment with respect to said base and said resistance element.

2. In a rheostat, a base member carrying a resistance element comprising in series a comparatively heavy wire coil and a comparatively fine wire coil, a pair of terminal plates mounted on said base, a rotatable sleeve adapted to be fastened to an actuating shaft and passing through said base and having a bearing therein, a contact plate fastened to said sleeve and having a contact finger in slidable engagement with said resistance element, and means associated with said base and independent of said shaft for holding said sleeve and attached finger in alignment with respect to said base and said resistance element, said means comprising a contact strip on one side of said base in engagement with said sleeve and with one of said terminal plates and comprising a spring member on the opposite side of said base and in engagement with said sleeve.

In witness whereof, I hereunto subscribe my name.

LAWRENCE C. F. HORLE.
